SNOWMOBILE SEAT

Anthony MacKeen and Yves Anselme La Pointe, Valcourt,
Quebec, Canada, assignors to Bombardier Limited,
Valcourt, Quebec, Canada

Filed Oct. 6, 1969, Ser. No. 19,432

Term of patent 14 years

Int. Cl. D12—16

U.S. Cl. D14—24

FIG. 1 is a side elevation view of the snowmobile seat showing our new design, the opposite side being a mirror image of the side shown.

FIG. 2 is a perspective view from the top, and one side thereof.

We claim:

The ornamental design for a snowmobile seat, as shown and described.
